UNITED STATES PATENT OFFICE

GLEN G. BARR, OF UNION CITY, INDIANA, ASSIGNOR TO BACKSTAY WELT COMPANY, OF UNION CITY, INDIANA, A CORPORATION OF INDIANA

GASKET

Application filed July 23, 1930. Serial No. 470,183.

My present invention relates to gaskets or weatherstripping for doors and particularly to the type which consists of a covering fabric folded upon itself and enclosing a packing element.

Gaskets of this general character have long been known in the art, and have comprised various arrangements of one or more soft fillers confined in a covering strip of fabric or the like provided with a portion adapted to receive tacks, nails, etc., for fastening the gasket in operative position in a door jamb. Such gaskets provide a fairly efficient seal when the door is closed on the jamb and the packing material in the filler is compressed therebetween.

I have found that insulation of considerably more efficiency can be obtained by associating with the customary soft and resilient filler of the prior art another filler of smaller diameter and less resilience and by interposing between the two fillers a thin but relatively wide portion of the covering fabric. This intermediate portion of the covering fabric serves to space the fillers apart and to provide between them a dead air space when the softer and larger filler is compressed between the door and the jamb to the thickness of the smaller filler. In this manner the gasket which forms the subject of the present invention operates to provide not only a double seal through contact of the door and jamb with each of the two fillers, but to provide also a third and more efficient non-conductive medium consisting of the dead air space between the fillers.

Another object of the invention is to provide a gasket which will retain for an unusually long period of time its original efficiency.

Other objects and advantages are inherent in the subject of my present invention the principles of which are pointed out in the appended claims and which is illustrated in one form of embodiment in the accompanying drawing forming part of this application for Letters Patent, in which

Figure 1 is a perspective view, with one end in section, of a gasket constructed according to the principles of the invention;

Fig. 2 is a sectional view of a portion of a door and a gasket applied thereto, with the door open; and

Fig. 3 is a view similar to that of Fig. 2 but showing the door closed against the jamb.

Referring now to the drawing, the reference numeral 1 designates a portion of the edge of any door, such for example as that of a refrigerator, and 2 indicates the jamb against which it is adapted to close.

The gasket comprises a covering fabric 3 of any suitable kind, such for example as oilcloth or equivalent textile material preferably provided with a hard, waterproof surface. The covering fabric is folded upon itself and encloses a plurality of fillers, at least one of which is relatively large and soft or resilient, and at least one of which is relatively small and hard or less resilient. In the exemplification of the invention illustrated in the drawing I have shown the gasket provided with two fillers, the reference numeral 4 indicating the large resilient filler, and the reference numeral 5 indicating the small hard filler.

The filler 4 is conveniently a rope or core of cotton wicking or the like, and the filler 5 I have found is best made of rubber. Both are normally cylindrical in form. They may be made of any materials and in any convenient shapes so long as they exhibit the differences in size and deformability which is characteristic of my invention.

The covering fabric 3 is folded along its longitudinal center around the filler 4 which is confined therein by a line of stitching 6. The fabric plies are then continued an appreciable distance in contact with each other to the line of stitching 7, beyond which they diverge to enclose the filler 5. The fabric is brought together beyond the filler 5 by the line of stitching 8, and the two plies are extended a substantial distance in contact with each other to provide a tacking flange or lap 9.

The gasket is applied in operative position to the edge of a door, or to a door jamb, by passing tacks, nails or the like through the tacking flange 9. The tendency among refrig-

erator manufacturers at the present time is to provide their doors with a metal flange spaced a slight distance away from the door proper, and it will be appreciated that the flange 9 may be readily inserted beneath such a flange and thus secured in place. The remainder of the gasket, including the two filler enclosing portions, projects outwardly to about the edge of the door, as shown in Figs. 2 and 3.

When the door is closed against the jamb the filler 4 is substantially deformed, becoming elliptical in section, as shown in Fig. 3. The sizes of the two fillers are so proportioned that when the door is fully closed and latched the filler 5 will be snugly engaged by both door and jamb under slight compression, and filler 4 will be deformed to an elliptical cross section having a thickness about equal to the diameter of filler 5.

It will be apparent from Fig. 3 that with the gasket in the condition there shown transfer of heat from one side to the other of the door which is sealed is prevented not only by the insulating fillers 4 and 5, but also by the very much more efficient insulation provided by the dead air spaces formed between the two fillers and the door and jamb, indicated at 10 in Fig. 3. It will be apparent, therefore, that my present invention, by providing in addition to the solid non-conductor seals of the prior art the dead air space which I believe to be novel with me, affords a highly superior gasket. It is to be noted also that my present gasket is considerably more durable than those of the prior art, i. e., it retains its high initial efficiency even after very long periods of use. This will be clear from the following considerations.

From the beginning of use of the gasket, filler 5 is compressed slightly each time the door is closed, and by being so compressed the extent to which the much softer filler 4 can be deformed is limited. Consequently, in gaskets made according to my present invention, the soft, resilient filler 4 is protected from the application of those severe compressive stresses which in the gaskets of the prior art soon cause induration and fibre consolidation and bring about steadily decreasing efficiency.

I am aware of prior gaskets which include with a wicking filler a strand, roll or rod of flexible material for the purpose of stiffening the soft wicking, of which United States Patent No. 1,742,195 to Bosley shows a typical example. I make no claim to any such stiffening element, the essence of my invention being the provision of a dead air space between two sealing fillers, a feature not achieved by the association of a mere stiffening element with a wicking filler.

I am aware also of structures which contain a relatively large sealing filler and a relatively small bead separated by an intervening

web of fabric, such as shown in the United States Patents No. 1,627,915 to Marshall and No. 1,713,268 to Dennis, and I make no claim to such combination, since it is of the essence of my present invention that the gasket have a plurality of sealing fillers which are adapted when in operation to provide between them a dead air space.

It is to be understood that various changes and modifications may be made in the practice of the present invention as exemplified in the specific gasket illustrated and described herein without departing from the principles thereof. Thus, for example, the fillers may be made of other materials than cotton wicking and rubber respectively, adhesive may be used to hold the plies of fabric together, the width of the web of covering fabric between the fillers may be varied somewhat, and other obvious changes may be made. All such modifications, however, to the extent that they exhibit the principles of the present invention as pointed out in the appended claims, are to be deemed within the scope and purview thereof.

Having thus described my invention what I claim and desire to secure by Letters Patent is:

1. A gasket adapted to be disposed between a door and its jamb having a fabric covering folded upon itself and enclosing a pair of fillers, one of said fillers being larger than the other and adapted to be compressed by closure of the door against the jamb to the thickness of the smaller filler.

2. A gasket adapted to be disposed between a door and its jamb having a fabric covering folded upon itself and enclosing a pair of fillers, the fabric being secured to itself between the fillers to provide a connecting web of relatively wide area lying substantially in a plane which passes diametrically through both fillers adapted to provide a dead air space on each side of said web when the gasket is compressed between a door and its jamb.

3. A gasket according to claim 1 in which the covering material is continued beyond the smaller filler to provide a tacking lap or flange.

4. A gasket according to claim 1 in which the smaller filler is of rubber and the larger filler is of fibrous material, and in which the covering material is continued beyond one of the fillers to provide a tacking lap or flange.

5. A gasket according to claim 1 in which the covering material is continued beyond one of the fillers to provide a tacking lap or flange.

In testimony whereof I affix my signature.

GLEN G. BARR.
